UNITED STATES PATENT OFFICE.

GEORGE HERBERT LANCHESTER, OF BIRMINGHAM, ENGLAND, ASSIGNOR TO THE
LANCHESTER MOTOR COMPANY LIMITED, OF BIRMINGHAM, ENGLAND.

VEHICLE-BONNET.

1,356,774.

Specification of Letters Patent. Patented Oct. 26, 1920.

Application filed November 25, 1919. Serial No. 340,487.

To all whom it may concern:

Be it known that I, GEORGE HERBERT LAN-
CHESTER, a subject of the King of Great
Britain and Ireland, residing at Armourer
5 Mills, Montgomery street, in the city of
Birmingham, England, have invented cer-
tain new and useful Improvements Relat-
ing to Vehicle-Bonnets, of which the fol-
lowing is a specification.

10 This invention has for its object to pro-
vide an improved bonnet for motor vehi-
cles and also means for securing the same.

The invention comprises the employment
15 of a pair of vertical sides and a top all of
which are hingedly connected in a separate
manner permitting the top to be disconnect-
ed from either side and swung back on the
other, or to be detached from both sides.
20 Further the invention comprises means for
fastening the interengaging edges of the
sides and top as hereinafter described.

In the accompanying sheet of explanatory
drawings:

Figure 1 is a cross section showing a mo-
25 tor vehicle bonnet constructed in accordance
with this invention.

Fig. 2 is a side elevation of a portion of
the bonnet showing one of the fastenings.

Fig. 3 is a section illustrating an alterna-
30 tive fastening.

In carrying the invention into effect as
shown, a pair of sheet metal sides *a* are
beaded along their upper edges, and the
35 adjacent edges of a sheet metal top *b* are
shaped to a grooved formation which en-
ables them to engage the beaded edges of
the sides and to be rotated thereon in a
hinge like manner. The lower edges of the
40 sides are hingedly and detachably connected
to lugs *c* or other pieces on the vehicle frame
in any convenient manner.

The interengaging edges of the top and
sides are held against accidental separation
45 by any suitable fastenings. Preferably the
fastenings are constructed from the follow-
ing combination. A metal plate *d* secured
beneath the beaded edge of a side and on
the inner or outer surface of the same is
50 provided with a boss *e* in which can both
slide and rotate a pin *f* carrying at its inner
end a claw *g* having a concave portion which
can grip the rounded edge of the top. A

spring *h* acting on the stem holds the claw
in engagement with the top. The spring
may be coiled around the stem as shown in 55
Fig. 1, or it may be constructed in the form
of a loop having one end secured to the
plate and the other arranged to abut on the
inner end of the stem as shown in Fig. 3.
At its outer end the stem is provided with 60
an operating handle *i* as in Figs. 1 and 2,
or adapted as shown in Fig. 3 for the appli-
cation thereto of an operating key. Two
or more such fastenings are fitted to each
side.

To open up the bonnet the stem of each
fastening on one side is first pressed in-
ward and then rotated. This releases the
fastenings from engagement with the top.
The top can then be detached from engage- 70
ment with that side and swung back on its
hinge connection with the other side. Thus
the top can be detached at either side while
retaining its connection with the opposite
side. The side from which the top is dis- 75
connected can be swung outward about its
lower pivotal connection with the chassis or
frame. Or the said side can be detached
from the frame. If desired the top can be
disconnected at both sides and lifted away 80
leaving both sides free.

Having thus described my invention what
I claim as new and desire to secure by Let-
ters Patent is:—

1. In motor vehicle bonnets, the combi- 85
nation comprising a top and a pair of sides,
means whereby the adjacent edges of the
said parts can be detachably engaged in a
hinge like manner, and spring controlled
means for detachably securing the said 90
edges, substantially as described.

2. In motor vehicle bonnets, the combi-
nation comprising a pair of sides and a top,
a bead along one edge of each side, and a
groove along a pair of edges of the top, the
bead and groove adjacent edges of the top
and side being adapted to permit a detach-
able hinge connection between said edges,
and spring controlled means for detachably
securing the interengaging edges of the top 100
and sides, substantially as described.

3. In motor vehicle bonnets, the combi-
nation comprising a pair of sides and a top, a
bead along one edge of each side, and a

groove along a pair of edges of the top, the bead and groove of adjacent edges of the top and side being adapted to permit a detachable hinge connection between said edges, a plurality of claws on each side capable of receiving longitudinal and rotational movements and adapted to detachably retain the

interengaging edges of the corresponding side and top in hinge connection, and a spring on each claw for retaining it in action, substantially as described. 10

In testimony whereof I have signed my name to this specification.

GEORGE HERBERT LANCHESTER.
